DIE STRUCTURE

Merle E. Halstead, Owego, N. Y.

Application September 24, 1936, Serial No. 102,384

12 Claims. (Cl. 164—29)

This invention relates to cutting and punching dies. Although applicable to various dies in different industries, the invention is primarily intended for use in the shoe industry, where a special difficulty in die equipment is encountered.

Common decorations on shoes include pinked edges, and rows of holes punched in the top layer of leather along seams by which adjacent uppers are joined. If the rearward edge or throat of the 10 vamp is to be pinked or decorated with a row of holes on a particular style of shoe having graded uppers, it is necessary for the manufacturer to have a different die for every size of shoe.

15 For another style of shoe a new set of dies is necessary, and since dies are expensive the capital investment required for decorating shoes becomes excessive, particularly in the case of women's shoes where variety is demanded and 20 it is customary to make only a limited quantity of the same style.

It is an object of this invention to provide a die structure in which inexpensive, interchangeable parts make it possible to change the contour 25 of the cutting apparatus to correspond to the shape of any size or style of shoe upper. The expression "cutting apparatus" is used herein as a generic term to describe a knife blade, such as used for pinking, or a series of punches for making decorative holes, or a combination of a blade and punches.

According to one feature of the invention, the cutting apparatus, instead of being set in a permanently fixed organization in the die structure 35 is retained by holders which are detachably held on a base and which can be maintained in a different relation for use with other styles or sizes of shoes by interchanging the cutting-apparatus holders for others of different shape. The advantage of such an organization is that the expensive parts of the die can be used for decorating uppers of different sizes and shapes, and the manufacturer need replace only the inexpensive 40 holders of the cutting apparatus when changing 45 to a different style of shoe.

The preferred embodiment of the invention employs the ribbon blade cutter disclosed in my Patent No. 2,078,569, dated April 27, 1937, and/or the chain of punches disclosed in my application Serial No. 102,383, filed September 24, 1936, but in its broad aspects the invention is not limited to die structures using the cutting apparatus of said patent and application.

Another object of the invention is to provide 55 an improved die structure which holds the cut-

ting apparatus at the correct height above the die holder of the machine, possesses the necessary strength, and will not warp or deteriorate in use, but which by virtue of novel features of its construction is much lighter than corresponding 5 die structures of the prior art. The inertia of my improved die structure is, therefore, less, and the manual labor of sliding the die back and forth between loading and cutting positions for each shoe upper decorated is so much reduced 10 that operators of less physical endurance can be employed to run the machines in which the die is used.

Another object of the invention is to provide improved means for holding the stripper plate 15 on the base of the die. Other objects, features and advantages of the invention will appear or be pointed out as the specification proceeds.

In the accompanying drawing, forming part 20 hereof:

Fig. 1 is a top plan view, with one-half of the stripper plate broken away, showing a die embodying the invention;

Figs. 2 and 3 are sectional views taken along the lines 2—2 and 3—3, respectively, of Fig. 1; 25 and

Fig. 4 is an enlarged detail view of a portion of the cutter chain.

The die illustrated comprises a base 11 on which cutter holding slides or plates 13 and 14 30 are held. These cutter holders 13 and 14 have confronting edges with a contour similar to that of the piece to be decorated, and they are spaced to form a channel 15 in which flexible cutting apparatus is placed and held to the desired 35 contour.

The cutting apparatus shown in the drawing includes a limber pinking blade 17 constructed of steel ribbon stock of such thinness that it requires lateral support in order to withstand the 40 cutting force. Such a blade having a thickness of .005-.015 inch cuts effectively without sharpening, and when corrugated for its full height is so limber that it can be bent around sharp curves including abrupt right angle bends. This 45 blade is disclosed in my Patent No. 2,078,569, dated April 27, 1937.

The cutting apparatus includes also a flexible chain 19 made up of blocks 21, 22 having overlapping lugs connected by pivot pins 23, as 50 shown in Fig. 4. A tubular punch 25 is secured to each of the blocks 21, and two similar, but smaller punches 26 are secured to each of the blocks 22. The punchings which enter the tubular punches are discharged through passages 28 55

opening through the sides of the blocks, as shown in Fig. 3. The detailed construction of such a chain of punches is shown in my copending application Serial No. 102,383.

5 The knife 17 and chain 19 rest on the base 11 and are held firmly in the channel between the holding plates 13 and 14 by clamping the holding plates in a manner hereinafter explained. The plates 13 and 14 are constructed of plywood. The edge of the holding plate 13 and the rearward faces of the blocks of chain 19 provide the lateral support for the knife 17. The holding plate 14 has channels 30 in its bottom face for the escape of punchings from the passages 28.

15 The base 11 is of laminated construction. That illustrated includes a metal base plate 32 on which rest the knife 17, chain 19, and holding plates 13 and 14. The die structure by which the cutting apparatus is supported must be of such 20 thickness that the cutting apparatus is located in correct operating position when the die structure is resting on the die holder of the machine with which the invention is to be used.

By combining the relatively thin metal base 25 plate 32 with plywood 34, which makes a laminated wooden base under the metal base plate 32, the cutting apparatus can be held at the desired height, and the weight of the die structure can be kept low. Wear of the bottom face of the 30 plywood would change the thickness of the die structure, but such wear is prevented by providing a metal surface or runners 36 on the bottom of the base 11. Flat head, countersunk screws 37 threading into the runners 36 clamp the edges 35 of the plywood between metal laminations of the base.

Undercut guides 39 are fastened to the base plate 32 along two parallel sides by screws 40. The cutter holding plates 13 and 14 have projections 41 extending into the undercut channels of the guides 39 so that the plates 13 and 14 are dovetail slides held on the underlying base by the guides 39.

A stop 43 extends across the base between the 45 guides 39 at their rearward ends. This stop 43 limits the movement of the holding plate 13 in a rearward direction. A clamping member 45 is drawn against the front edge of the holding plate 14 by screws 46 that thread into nuts 47 50 embedded in the plywood 34. There is a recess 49 in the front edge of the base 11 for punchings in the channels 30 to drop through. Without this recess the escape of punchings from the channels 30 would be blocked by the clamping member 45.

By removing the screw 46, the clamping member 45 can be taken off and the cutter holding plates 13 and 14 can then be slid forward and removed from the die structure. Other plates 60 which form a different contour channel for holding the cutting apparatus can be inserted in place of the plates 13 and 14. If the knife 17 is to be used without the chain 19, a narrower channel is required, since the edge of the forward 65 cutter holding slide has to clamp the ribbon knife against the rearward slide.

The plywood cutter-holding slides can be made with a jig or band saw to a contour corresponding to the shape of the piece to be pinked 70 or decorated. The same knife 17 and chain 19 can be used with slides having different contour edges. The invention makes it possible for a manufacturer to decorate a wide variety of shapes and styles of shoe uppers with one base 75 11 and interchangeable cutter-holder slides for

shaping the knife 17 and chain 19 to the contour of the edge to be decorated.

The material which is to be punched and pinked is supported above the cutting apparatus by a stripper plate 51. Studs 52 extend downward from the stripper plate into openings 53 (Fig. 2) in the base 11. A bushing 55 surrounding each of the studs 52 has a recess 56 and is held at a definite level in the opening 53 by a clip 57, the ends of which extend through the recess 56. The clips extend through holes in the plywood 34 just below the metal plate 32, and are held firmly in the base by friction. When these clips 57 are inserted in the base as far as the length of the holes will permit, their mid-10 portions extend beyond the side of the base so that they can be hooked or gripped firmly when they are to be withdrawn.

A spring 60 surrounding each of the studs 52 is compressed between the stripper plate 51 and the bushing 55. A screw 62 threaded into the lower end of the stud 52 limits the upward movement of the stud, and since the bushings 55 are held at definite levels by the clips 57, the springs 60 hold the stripper plate at a definite level with 20 the top of the plate slightly higher than the cutting edges of the punches 26 and flexible blade 17.

The stripper plate 51 has a slot 64 over the cutting apparatus, the slot being, of course, the same in contour as the channel between the plates 13 and 14, though not necessarily of the same width.

The shoe upper, or other sheet, to be decorated is positioned with respect to the cutting apparatus by pushing the edge of the sheet against formation studs 66. These studs extend through slots 66a in the stripper plate and are bent-up portions of springs 67 connected to the stripper plate by rivets 68 which are located at a distance 40 from the formation studs 66 in order to permit the springs 67 to bend and the formation studs to move down flush with the top surface of the material being cut when the die is in use.

Whenever other cutter holder slides are interchanged with the holders 13 and 14 to obtain a different shape of channel for the cutting apparatus, it is necessary to change to a new stripper plate having a channel corresponding to that between the cutter-holder slides. The 50 clips 57 are withdrawn and the stripper plate can then be lifted clear of the base. A new stripper plate is placed in position with its bushings 55 in the openings 53 and the clips 57 are again inserted.

The stripper plate is of thin metal and is an inexpensive part of the die. The cutter-holder slides 13 and 14 are even less expensive and it will be apparent, therefore, that this invention greatly reduces the cost of equipment necessary 60 for cutting and punching different sizes and styles of shoe uppers. The same cutting apparatus is used for all sizes and styles. There is no expensive setting of punches or cutters in fixed organizations useful for decorating an edge 65 of only one contour.

The die structure of this invention is not limited to the particular embodiment which has been illustrated and described, and features of the invention may be used without others.

I claim:

1. A cutting die comprising a flexible cutter, a base supporting the flexible cutter, complementary members on the base on opposite sides of the cutter shaped to form a channel of permanent 75

contour for holding the flexible cutter to the desired outline to be cut, and means detachably securing the holding members in position so that said members are readily interchangeable with others of different contour.

5 2. A die structure including a base, guides secured to and extending along two sides of the base, two cutter holders held in position on the base by the guides, said holders having confronting edge faces shaped to the contour of the cut to be made, and a clamp for moving the cutter holders toward one another to clamp cutting apparatus between said confronting edge faces.

10 3. In a die structure, a base, cutter holders having spaced edges forming a channel for holding the cutter apparatus, retaining means for keeping the cutter holders on the base and for preventing lateral displacement of them on the base, and clamping means adapted to move the cutter holders together to reduce the width of the channel which they form.

15 4. Apparatus for punching a series of decorative holes along the edge of a shoe upper or other work, said apparatus comprising a plurality of punching devices, a supporting base on which the punching devices rest, two plates fastened to the base and having cooperating edge faces between which the punching devices are held to maintain them on a line having the contour desired, and a channel between the base and one of the plates for the escape of punchings.

20 5. A die structure comprising a laminated base having a relatively thin metallic top plate for supporting the cutting apparatus, metal covering over at least a portion of the bottom face of said base, a relatively light non-metallic section between the top plate and metal of the bottom face, said non-metallic section comprising the greater part of the thickness of the base, and means above the top plate for holding the cutting apparatus against displacement on said plate.

25 6. In a die structure, a metal supporting plate for the cutting apparatus and means for holding the cutting apparatus against displacement on said plate, plywood laminations secured to the under side of the metal plate and increasing the thickness of the die structure to raise the level of the cutting apparatus when the die structure is in the cutting or perforating machine with which it is intended to be used, and a metal bottom under the plywood and adapted to keep the plywood out of contact with the die support of the machine.

30 7. A die structure including a laminated base comprising a relatively thin metal plate, plywood laminations under the plate, metal covering at least a portion of the bottom face of the lowest plywood lamination, the combined thickness of said plywood laminations being substantially greater than the thickness of said metal plate, and means uniting the wood and metal laminations into a unitary base, guides fastened to the top of the base along two sides of the base, said guides having channel recesses in their confronting edge faces, two slides extending between the guides and projecting into the channel recesses, and spaced edge faces on the slides defining a channel for holding to a desired contour flexible cutting apparatus resting on the metal plate.

35 8. A die structure including a laminated base comprising a relatively thin metal plate, plywood laminations under the plate, metal covering at

least a portion of the bottom face of the lowest plywood lamination, the combined thickness of said plywood laminations being substantially greater than the thickness of said metal plate, and means uniting the wood and metal laminations into a unitary base, guides fastened to the top of the base along two sides of the base, said guides having channel recesses in their confronting edge faces, two slides extending between the guides and projecting into the channel recesses, 10 spaced edge faces on the slides defining a channel for holding to a desired contour flexible cutting apparatus resting on the metal plate, a clamping plate at one end of the base and extending above the base and across the end face 15 of one of the slides, a screw for drawing the clamping plate toward the base and urging one of the slides toward the other to clamp the cutting apparatus in the channel between the slides, and a member embedded in the plywood with 20 threads for holding said screw.

9. In a cutting and punching die, a laminated base having a metallic top plate and plywood laminations under the top plate, a stripper plate, 25 studs extending downward from the stripper plate, a bushing freely fitting around each of said studs, stops at the lower ends of the studs to keep the bushings from coming off the studs, openings in the base into which the bushings fit, clips extending through the plywood just beneath the top plate and held in position by friction against the plywood, each of said clips extending across a shoulder on an adjacent bushing to hold the bushing in the opening in the base, and a spring surrounding each of the studs and compressed 30 between the bushing and the stripper plate.

10. In a cutting or punching die, a base, bushings detachably held in the base, a stripper plate, studs extending downward from the stripper plate and through the bushings, a stop at the lower end of each stud to limit its upward movement through the bushing, and a spring compressed 40 between the stripper plate and each of the bushings.

11. Improvements in dies comprising a stripper plate for yieldingly supporting a piece of work over cutting apparatus on a base, said stripper plate resting on springs and having studs extending into bushings located in, but readily removable from the base.

45 12. A cutting die comprising a flexible cutter, a base supporting the flexible cutter, members on the base on opposite sides of the cutter and forming a channel of a given shape for holding the flexible cutter to the desired contour to be cut, 55 means detachably securing the holding members in position so that said members are readily interchangeable with others of different contour, a stripper plate above the base and having a slot with a contour corresponding to that of the 60 channel which holds the flexible cutter, studs extending downward from the stripper plate, a bushing around each stud, a stop at the lower end of each stud to limit its upward movement through the bushing, a spring compressed between the stripper plate and each of the bushings for yieldably holding the stripper plate above the base and cutter, and clips extending through the base and into the bushings for detachably connecting the bushings and the base.
